J. H. HAMLIN.
BORING MACHINE.
APPLICATION FILED MAR. 16, 1921.

1,434,891.

Patented Nov. 7, 1922.

UNITED STATES PATENT OFFICE.

JOSEPH H. HAMLIN, OF WINSTON-SALEM, NORTH CAROLINA.

BORING MACHINE.

Application filed March 16, 1921. Serial No. 452,842.

To all whom it may concern:

Be it known that I, JOSEPH H. HAMLIN, a citizen of the United States, and a resident of Winston-Salem, in the county of 5 Forsyth, in the State of North Carolina, have invented certain new and useful Improvements in Boring Machines, of which the following is a specification.

This invention is a boring tool especially 10 adapted for boring the bearing faces of connecting rods and other bearings.

Briefly stated, an important object of this invention is to provide a boring tool for bearings having attaching means which 15 properly position the cutting devices so that as the cutting devices are passed through the work, the same will provide the inner face of the bearing with a smooth and round surface.

20 A further and equally important object of the invention is to provide a boring tool for sectional bearings having attaching arms which are adapted to be confined between the sections of the bearings for temporarily taking the place of the shims which 25 are ordinarily employed so that the liner of the bearings may be cut while in the same position which they occupy when in use.

30 A further object of the invention is to provide a boring machine of the class described having attaching arms provided with opposed straight edges which function as a gauge when adjusting the cutters.

35 A further object of the invention is to provide a boring machine which may be used on an internal combustion engine for cutting the bearings of the same without the necessity of elaborately dismantling the engine.

40 A further object of the invention is to provide a device of the class described which is efficient in use, of highly simplified construction and cheap to manufacture.

45 Other objects and advantages of the invention will be apparent during the course of the following description.

In the accompanying drawings, forming a part of this application and in which like 50 numerals are employed to designate like parts throughout the same,

Figure 1 is a side elevation of the improved tool.

Figure 2 is a plan view of the same, the 55 handle being removed.

Figure 3 is a vertical transverse sectional view taken on line 3—3 of Figure 1.

Figure 4 is an end elevation of the improved boring tool applied to a connecting rod, for the purpose of boring the lining 60 of the same.

Figure 5 is a fragmentary perspective of a screw embodied in the invention.

Figure 6 is a detailed sectional view 65 through the cutter head.

Figure 7 is a sectional view through the cutter head taken at right angles to Figure 6.

In the drawing, wherein for the purpose of illustration is shown a preferred embodiment of the invention, the numeral 10 designates a cross head which is provided with an elongated interiorly screw threaded boss 11 through which is threaded a feed screw 12. It will be noted that the sleeve 11 is of 70 a substantial length so as to hold the screw 12 properly aligned with the longitudinal axis of the bearings to be drilled. By reason of this construction, the strain on the cutter will not throw the feed screw 12 out of line. As illustrated in Figures 2 and 3 the cross 75 head 10 is provided with a pair of longitudinal slots 11' which extend out through the ends of the head and slidably receive the shanks 12' of a pair of attaching arms 13.

The shanks 12' are slidable within the 80 slots 11' and may be held in an adjusted position by means of nuts 14 which are threaded onto the shank. Washers 15 are confined between the nuts 14 and the upper face of the head 10.

It might be stated that a tool constructed in accordance with this invention is preferably made from tool steel highly finished so that the parts are capable of accurate adjustment. It will be noted with reference 85 to Figure 3 that the rear portion of each arm is provided with a pair of laterally projecting shoulders 16 which flatly contact with the under side of the cross head so as to prevent tilting of the arms 13 with relation to the head 10.

The arms 13 form an attaching means for the device and are adapted to be received between ears 17 of a sectional bearing designated by the numeral 18. In Figure 4 I have 105 illustrated the bearing 18 as a part of a connecting rod 19 of an internal combustion engine though it is obvious that the bearing operated on may be the main bearing of an internal combustion engine or any other ma- 110

chine. The forward portion of the arms 13 are extended inwardly to form what might be termed hooks 20 which engage about the shanks of bolts 21 employed for connecting the ears 17. The inner sides of the hooked terminal portions 20 are formed with recesses or notches 22 which receive portions of the bolt shanks and thereby hold the device firmly in position. It is understood of course that the nuts 24 on the bolts 21 are tightened so as to firmly engage the ears 17 with the inwardly directed terminal portions 20 of the arms 13. By firmly securing the terminal portions 20 of the arms between the ears 17, the device is accurately arranged in its operative position and when the cutting mechanism is engaged with the Babbitt liners or the anti-friction element 25, a true cut will be made.

As is customary, shims are ordinarily arranged between the ears 17 to space the same and as the anti-friction elements 25 which are of semi-circular formation wear, certain of the shims are removed so as to compensate for the wear. In other words the wear in the bearings is compensated for by removing certain of the shims. Therefore it is desirable to provide for these shims when drilling the bearings. As illustrated in Figure 4, the terminal portions 20 take the place of the shims and thereby cause the semi-circular anti-friction elements 25 to assume their final position with relation to each other when being drilled or faced. It is thus apparent that the arm 13 not only serves as a means to secure the device in position but also to form a means to properly space the sections of the bearings and to take the place of the shims which are ordinarily used to space the sections of the bearing. By reason of this construction the liners 25 of the bearing are cut perfectly true.

The forward portion of the feed screw 12 is provided with a cutter head which includes stationary and removable disks 30 and 31 respectively. The removable disk 31 is held in position by a nut 32 which is threaded on the shank 33 formed on the forward end of the screw in advance of the stationary head 30. A pair of spaced parallel cutters 34 are confined between the sections of the cutter head and have their end portions beveled and sharpened as indicated at 35 so as to cut the inner side of the semi-circular bearing.

In adjusting the cutters to move in a circular path, the beveled ends of the same may be positioned between the opposed spaced parallel straight edges 36 of the terminal portions of the arms so that the zone of action of the cutters may be properly adjusted. A rule or other measure may be employed for ascertaining the correct distance between the straight edges 36. Should it be desired to cut a bearing exactly two inches

in diameter, the arms 13 are adjusted so that there will be a space of exactly two inches between the same and the cutter head is subsequently advanced and the cutters 34 adjusted so that they will contact with the straight edges 36 at the same time. At this time, the arms 13 function as a gauge.

With reference to the foregoing description taken in connection with the accompanying drawings, it will be apparent when the device is applied the same is firmly held in position by the ears 17 so that as the cutting members are passed through the semi-circular bearings 35 an accurate cut will be made. In carrying out the invention the threads on the feed screw are preferably left hand and very fine so that the feeding will be very gradual.

The device in use is durable and is very accurate. Also by reason of its construction the same may be applied either to the main bearings or to the connecting rod bearings of an internal combustion engine.

A handle 40 is detachably connected to the rear portion of the feed screw and may be manually rotated imparting a corresponding movement to the feed screw. The rear end of the feed screw is provided with a squared attaching portion 41 which passes through a longitudinal slot in the handle 40. A thumb screw 41 is threaded onto the rear end of the feed screw so as to hold the handle in an adjusted position on the feed screw.

It is to be understood that the form of the invention herewith shown and described should be taken as a preferred example of the same and that such minor changes in arrangement and construction of parts may be made as are within the spirit of the invention and the scope of what is claimed.

Having thus described my invention, what I claim is:—

1. A boring machine for sectional bearings comprising a pair of combined attaching and spacing arms having their terminal portions hooked for engagement with the connecting means of the sections of a bearing, and a cutter carried by and positioned by said arms.

2. A boring machine for sectional bearings comprising attaching arms adapted to be arranged between the sections of a bearing whereby to space the sections, and a cutter associated with and positioned by said arms.

3. A boring machine for sectional bearings comprising a pair of attaching arms adapted to be arranged between the sections of a bearing to space the same, a cutter positioned by said arms, and a feeding device for the cutter.

4. A boring machine for sectional bearings comprising a pair of attaching arms adapted to be arranged between the sections of a bearing to space the same, a cutter as-

sociated with said arms, a feeding device for the cutter, and means connecting the feeding device and said arms.

5. A boring machine for sectional bearings comprising a head, attaching arms carried by said head and adapted to be confined between the sections of a bearing for positioning the machine and for spacing the sections of a bearing, and a cutter arranged between said arms.

10. A boring machine for sectional bearings comprising attaching arms adapted to be arranged between the sections of a bearing whereby to space the sections, and a cutter associated with and positioned by said arms, portions of said arms having their opposed edges parallel to constitute a gauge for said cutter.

15. A device of the class described comprising a head, attaching and spacing arms adjustably carried by the head and having straight edges constituting a cutter gauge, and a cutter arranged between and positioned by said arms and movable with relation to the same.

20. A boring machine for sectional bearings comprising a head, attaching arms carried by the head and adapted to be arranged

between the sections of a bearing whereby to space the same, a cutter arranged between 30 said arms and movable with relation to the same, and a feed screw connected to said head and supporting said cutter.

25. A boring machine for sectional bearings comprising a head, attaching arms carried by said head and adapted to be arranged between the sections of a bearing, a boss formed on said head, a feed screw threaded through said boss, and cutters connected to the forward end of said feed screw, 35 said arms also forming a means to space the sections of a bearing during the cutting operation.

30. A boring machine for sectional bearings comprising a head, attaching arms adjustably carried by said head and adapted to be arranged between the sections of a bearing whereby to space the sections, a boss formed on said head, a feed screw threaded 40 through said boss, a cutting device connected to the forward end of said feed screw, and laterally projecting shoulders formed 45 on said arms and contacting with the under side of said head.

JOSEPH H. HAMLIN.
